CLAIM

The ornamental design for a bottle, as shown and described.

DESCRIPTION

FIG. 1 is a front view of the bottle of our new design, the bottle body at the upper end of the bottle, the closed dispenser cap at the lower end of the body, and the locking ring between the bottle body and the dispenser cap as viewed in FIG. 1.

FIG. 2 is a front view of the bottle body and of the dispensing end of the dispenser cap, the dispenser cap removed and separated from the bottle body, the dispenser cap open with the lid of the dispenser cap swung from the base of the dispenser cap.

FIG. 3 is similar to FIG. 2 but with the dispenser cap closed.

FIG. 4 is similar to FIG. 2 but with the dispenser cap on its side.

FIG. 5 is similar to FIG. 2 but with the bottle body lying on its side with a view into the open lower end of the bottle body as viewed in FIG. 1.

FIG. 6 is similar to FIG. 2 but includes a side view of the bottle body and includes a view of the lower end of the locking ring as viewed in FIG. 1 that attaches the dispenser cap to the locking ring; and,

FIG. 7 is similar to FIG. 6 but includes a view of the locking ring on its side and includes a view of the upper end of the locking ring as viewed in FIG. 1 that attaches the locking ring to the bottle body.

No color is claimed as part of the design.
